CONTROL FOR POWER OPERATED WRINGERS

Edmund I. Tooker, San Francisco, Calif.

Application April 22, 1936, Serial No. 75,854

4 Claims. (Cl. 192—129)

My invention relates to improvements in power operated washers of the domestic type and having a wringer, a motor for driving said wringer and gear shifting means for operatively connecting and disconnecting said wringer with and from said motor and the invention comprises improved means for automatically disconnecting the motor from its power source when the wringer is operatively connected to said motor, said means operating in conjunction with manual means, preferably foot-operated, for manually reconnecting the power source to said motor whereby said wringer may be operated only under manual control.

The primary object of the present invention is to provide a new and improved control for power operated wringers.

Another object is to provide new and improved means whereby operation of a power operated wringer may be automatically discontinued when an operator thereof leaves the immediate vicinity of said wringer, in order to avoid accidental injury to children and others, when said wringer is unattended.

A further object is to provide new and improved means for controlling the operation of a power operated wringer whereby operation of said wringer may be more easily and quickly stopped in case of accident or other necessity.

I accomplish these and other objects by means of the preferred form of the invention disclosed in the drawing forming a part of the present application, and in which—

Fig. 1 is a partly broken front elevation of one type of domestic washer disclosing my invention applied thereto;

Fig. 2 an enlarged, broken detailed view, in section, of a portion of the gear-shift of a washer with one of the controlling elements;

Fig. 3 is a side elevation of Fig. 2, in section and showing greater detail;

Fig. 4 is an enlarged sectional view of the normally open and manually closable switch; and

Fig. 5 is a diagram of the electrical circuit of my invention.

Referring to the drawing:

The numeral 1 is used to designate in general a power operated domestic washer or washing machine, having the usual motor M, a power operated wringer 2 and a gear-shift 3 for operatively connecting and disconnecting said wringer 2 with and from said motor M. As the types of gear connections on such washers are so varied and so thoroughly understood in the art, a detailed illustration and/or description of any particular type of gear connection or gear-shift, is

considered superfluous and unnecessary, and more especially as such connections form no part of the present invention.

It is sufficient to say that upon the gear-shift 3 I have provided a cam 4 by cutting away a portion of the stem of said gear-shift 3, said cam 4 being positioned to move a thrust rod 6, of any suitable insulating material, to open a switch 7 arranged in series with the motor switch 9 connecting the motor M with a power source 11, when said gear-shift 3 is in any but a neutral position, as disclosed in Figs. 2 and 3 of the drawing, so that notwithstanding that the switch 9 is closed to connect the power source 11 with the motor M, that movement of said gear-shift 3 from a neutral position will open the switch 7 and stop further motion of said motor M and the wringer 2.

A normally open switch 12 is connected in parallel with the switch 7 and also in series with the switch 9 of the motor M and is mounted within a suitable housing 14 upon a floor-plate 16 and actuated by means of a pedal 17 hingedly mounted upon said plate 16 and normally operated by a suitable spring 18 interposed between said pedal 17 and plate 16, to normally retain said switch 12 open by means of an insulated push-rod 19, as disclosed in Fig. 4 of the drawing. The second switch 12 is preferably placed upon the floor adjacent the washer 1 and closed manually by foot pressure upon the pedal 17, in order to leave the hands of an operator free for manipulating the washer and its several parts, such, for instance, as the gear shift 3 for reversing the direction of rotation of the wringer 2 or the switch 9 which controls the motor M or in attending to the washing operation.

In operation

The main switch 9 is closed to connect the motor M with the power source 11 which, in the usual manner, operates the washing mechanism, not shown, as well as the gearing or other mechanism for operating the wringer 2. As is well known in the art of washing clothes with such washers, there comes a time when it is required to wring the clothes while passing from one tray or tub, of which there are usually at least two, to another. This is, in the present state of the art as well as with the present invention, accomplished by moving the gear-shift 3 from the neutral position marked "N" to the position marked "F" in Fig. 2 of the drawing, for operating the wringer 2 in a forward direction, and to the position marked "R" for reversing direction of rota-

power washer having said wringer, for said motor, and relatively connecting wringer, of means automatically shifting means for said motor from said shifting means connecting said wringer operated means for 10 said power source separating means be operated coextensive of an operator 15

15 a electrically driven motor for driving said source for said motor, operatively connecting motor, of a switch 20 power and automatically shifting means, when operated with said motor, said power source; manually closable 25 source and in parallel connect said source of said first switch be operated only coextensive of said second switch.

30 n electrically driven motor for driving said source for said motor, operatively connecting wringer with and connected with said means connected to said motor, of a wringer with said and thereby disconnecting power source; and a manually closable switch source and in parallel connect said power source by said wringer may be operated only with manual closing operation of said n said washer is unholding closed said 50

UND I. TOOKER.

tion of said wringer. But, in the present case, when the gear-shift 3 is moved to operatively connect the wringer 2 with the motor M the cam 4 will, through the insulated rod 6, open the switch 7 and thereby disconnect the motor M from its power source 11 and rotation of the wringer is instantly stopped.

If the normally open switch 12, in series with the main switch 9 and in parallel with the switch 10 7, is now closed by foot pressure upon the pedal 17, the source of power 11 will instantly be reconnected with the motor M and said motor will immediately operate and in turn operate the wringer 2 in the direction selected and the said 15 wringer will continue to be operated by said motor just as long as foot pressure is continued upon the pedal 17 to close the normally open switch 12. The instant that such foot pressure is released from said pedal 17 the switch 12 will be opened 20 by the tension of the spring 18 and operation of the wringer 2 will cease.

25 Manual closure of the normally open switch 12 by means of foot pressure, or manual operation, leaves the hands of an operator free to manipulate the progress of clothing through the wringer 2 or to perform any other required operation. If, for any reason, it is desired to suddenly stop the operation of the wringer it is only necessary to remove foot-pressure from the 30 pedal 17.

35 The prime advantage of this novel arrangement is that if the operator is suddenly interrupted or her presence required elsewhere, the motion of the wringer 2 will be automatically stopped as soon as said operator leaves the immediate vicinity of the washer, thereby preventing accidental injury to children or to clothes bunching in the wringer or any other damage which may ensue from a continued unattended 40 operation of the wringer.

Having described my invention I claim—
1. The combination with a power washer having a wringer, a motor for driving said wringer, including a power source for said motor, and means for operatively connecting and disconnecting said wringer with and from said motor, of means for automatically separating said motor from said power source when said connecting means are actuated to operatively connect said wringer with said motor; and manually operated means for re-connecting said motor with said power source, independently of the said separating means.

2. The combination with a power washer having a wringer, a motor for driving said wringer, including a source of power and gear shifting means for operating said wringer with said motor, automatically actuated by said gear shifting means for automatically separating said source of power when said gear shifting means are actuated to operatively connect said motor with said power source; and foot-controlled means for re-connecting said motor with said power source independently of said power source, whereby said wringer may be stopped by the foot-pressure on the pedal 17.

3. The combination with a power washer having a wringer, a motor for driving said wringer, including a power source and gear shifting means for operating said wringer with said motor, controlling said source of power by gear shifting means automatically actuated by said gear shifting means, moved to connect said motor with said power source and a normally open and normally closed switch connected with said gear shifting means, with said first switch to re-connect said motor with said power source independently of said power source, whereby said wringer may be stopped by the foot-pressure on the pedal 17.

4. The combination with a power washer having a wringer, a motor for driving said wringer, including a power source and gear shifting means for operating said wringer with said motor, of a switch for connecting said motor with said power source and operatively connecting and disconnecting said motor with said power source, when moved to connect said motor, to open said switch and disconnect said motor from said power source, normally open and manually controlled to said power source with the first switch to re-connect said motor with said power source with said motor where said switch is operated only coextensive with the second switch, and the wringer is discontinued when the second switch is discontinued; and a pedal for normally opening said switch.
